UNITED STATES PATENT OFFICE.

PETER M. DALTON, OF EVERSON, PENNSYLVANIA.

CAR-BRAKE.

SPECIFICATION forming part of Letters Patent No. 249,226, dated November 8, 1881.

Application filed April 16, 1881. (No model.)

To all whom it may concern:

Be it known that I, PETER M. DALTON, of Everson, in the county of Fayette and State of Pennsylvania, have invented a new and useful Improvement in Railroad-Brakes; and I do hereby declare the following to be a full, clear, and exact description thereof, reference being had to the accompanying drawings, forming a part of this specification, in which—

10 Figure 1 is a plan view, showing my improved brake as it may be applied to railroad-cars. Fig. 2 is a side elevation of the draw-head and spring as adapted to my invention. Fig. 3 is a detached plan view of the auxiliary spring on the end of the draw-head beam as adapted in my invention. Fig. 4 is an end view of the same; and Fig. 5 is a plan view, showing the side of the same without the spring.

Like letters of reference indicate like parts 20 in each.

My invention relates to that class of brakes for railroad-cars, by means of which the engineer can control the motion of the train; and it consists in certain combinations with the 25 brake-lever, brake rod or staff, and brake-chain or like flexible connection between the brake-lever and brake-staff, of a movable or sliding draw-head, which acts directly upon the brake-chain, and of fulcra arranged upon the car-bed 30 in the path of the brake-chain, and with relation to the movable or sliding draw-head, so that the direct thrust of the draw-head shall take up the slack of the brake-chain and by its 35 direct action apply the brakes, and in combining with the movable draw-head a relief-spring arranged on the rear end of the same, to prevent the rupture of the brake-chain by the sudden thrust of the direct-acting draw-head, all as will hereinafter more fully appear.

40 I will now describe my invention according to the modification shown in the drawings.

a represents a portion of the bed of a railroad-car; *b*, the wheels; *c*, the axle; *d*, the draw-head; *e*, the spiral spring in the cylinder; *e'*, 45 cylinder which is attached to the frame of the car, the purpose of the spring *e* being to act as a cushion when the draw-head is pushed in by the cars coming together.

f is an extension of the draw-head beam, on 50 which, beyond the spring *e* and cylinder *e'*, is a collar, *g*. Beyond this collar *g* is a cylinder, *h*, through which the end of the draw-head

beam passes. Inside of this cylinder is a spiral spring, *i*, and at the end of the cylinder next the collar *g* is a disk, *k*, which rests against the spring in the cylinder. Beyond the cylinder *h* are two pulley-wheels, *l* *l'*, attached to the frame of the car; and between and beyond these wheels is another pulley-wheel, *m*, which is pivoted in a U-beam, *n*, which extends from the far end of the cylinder *h*.

o is the brake-lever, which may be of the usual form.

p is the brake-chain, which passes from the brake-lever *o* over the front of the wheel *l'*; thence over the back of the wheel *m* in the U-beam *n*, and thence over the front of the wheel *l*, to the brake-rod *q*, which may be of the usual form, extending to the top or side of the car.

The operation of this device is as follows: The 70 chain *p* being wound around the brake-rod *q* sufficiently to take in the slack, when the engineer desires to put on the brakes he applies the brake to the engine, which causes the cars of the train to push against each other by reason 75 of their momentum. This thrusts in the draw-heads, the spiral spring *e* offering sufficient resistance to prevent a jar which would injure the cars. The collar *f* pressing against the disk *k* carries the cylinder *g*, U-beam *n*, and wheel 80 *m* with it, which wheel *m* draws the chain *o*, and thereby moves the brake-lever *q* sufficiently to put on the brakes, or causes them to press against the wheels *b* of the car. The spring *i* acts as a cushion to prevent the sudden thrust 85 of the draw-head beam from breaking the chain *p*, and also to prevent more than a certain amount of strain being put on the chain *p* after the brakes are applied. By the arrangement 90 of the pulley-wheels *l*, *l'*, and *m* the portion *p'* of the chain *p* is caused to move twice the distance traveled by the wheel *n*; and by attaching the end of the chain *p* to the brake-lever *o* at a point nearer the fulcrum, the distance 95 over which the lever will travel may be increased. In order to release the brakes the engineer has simply to start his engine.

When it is desired to back the train without at the same time putting on the brakes, the brake-rod *q* should be released, thereby slackening the chain *p* sufficiently to prevent the brakes being applied by the inward thrust of the draw-head. By this arrangement of the different parts the brakes may be put on one or all of

the cars in the train by the inward thrust of the draw-head, as this thrust does not apply the brakes to those cars on which the chain has not been tautened by the brake-rod; and, 5 if desired, the brakes may be applied by the brake-rod in the usual manner. In case the brakes have been applied by the brake-rod, and the draw-head should be pressed in by two cars coming together, the force will be 10 taken up by the spring *i*, and thereby prevent the chain or other parts of my device from being broken; or an extra chain may be used, by means of which the brakes may be applied by the brake-rod without tautening the chain *p*. 15 The advantages of my invention are that it is simple, cheap, and easily applied. By its use the engineer can have complete control over the train, and can by simply shutting off the steam and applying the brakes to the engine and tender cause the cars of the train to come together, and thereby quickly bring them to a stand-still. By its use the number of brakemen needed on a train will be reduced, and the liability to accidents lessened. 20 What I claim, and desire to secure by Letters Patent, is— 25

1. The combination, in an automatic car-brake, of a brake-lever and a brake-staff, the two directly connected by a brake-chain or like

flexible connection, fulcra arranged on the car-bed in the path of the brake-chain, and a sliding draw-head arranged to act directly on the brake-chain and take up the slack thereof by forcing the chain between or around the fulcra, the several elements being relatively arranged 30 and coacting substantially as and for the purpose specified.

2. The combination, with the brake-lever, the brake rod or staff, and the brake-chain or flexible connection between the same, of the movable draw-head having a pulley on its rear end, and the two pulley-wheels arranged in the path of the brake-chain and on either side of the movable draw-head, substantially as and for the purpose specified. 40

3. The combination, with the brake-lever, brake-chain, and fulcra located on the frame of the draw-head in the path of the brake-chain, of a movable draw-head having at its inner end the pulley-wheel and spring relief mechanism, substantially as and for the purpose specified. 45

In testimony whereof I have hereunto set my hand.

PETER M. DALTON.
